UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRICAL CONNECTER DEVICE.

Application filed February 16, 1924. Serial No. 693,257.

This invention relates to fittings for electrical fixtures, and is of particular utility when embodied in connectors use for the mechanical and electric attachment of electric 5 lighting fixtures to outlet receptacles installed in the walls of a building. An important object is to provide an attachment plug for such connectors of insulating material and so constructed as to afford the necessary insulating effect and the requisite resistance to deformation or fracture under 10 the strains which it must experience, in service, and notwithstanding the restricted space within which it must be assembled.

15 In carrying the invention into effect such attachment plugs are formed of laminæ of fibrous material connected to form a unitary structure, being provided with electrical contact parts so united with, and supported by 20 the laminated structure, that the attachment plug thus formed is more compact, more durable, and cheaper to construct, than existing molded plugs.

In the drawings, Fig. 1 is a side elevation 25 of a connector device illustrating the invention; Fig. 2 is a vertical section of the same, with parts shown in elevation; Fig. 3 is a rear elevation of the plug member, isolated from its receptacle; Fig. 4 is a longitudinal section of the isolated plug, on the line IV—IV of Fig. 3; Fig. 5 is a section on the line V—V of Fig. 4; Fig. 6 is a perspective of the plug; Fig. 7 is a similar view in reversed position; and Fig. 8 is an exploded 30 view of the component parts of the attachment plug.

Appliances of the type illustrated comprise 35 respectively a metal shell 1 which sustains the mechanical strain of supporting the weight of the lighting fixture such as a conventional wall lamp bracket or sconce, with its electric lamps and their shades; and an attachment plug 2 of insulating material, movably enclosed within the aforesaid metal 40 cover or shell and which carries a pair of projecting metal contact parts or prongs 3 having binding screws 4 (see Fig. 3) to which are connected the fixture wires leading through the shell and fixture to the lamp.

45 The shell 1 has a pair of hooks 5, of which one is shown in Fig. 1 and the other appears in Fig. 2, which are adapted to hook into slots provided in the face-plate 6 of the wall-receptacle, of which only the face-plate

is shown. A hook projection 7 on the lower 55 portion of the shell is adapted to enter a slot in the lower part of the plate and is provided with a suitable latch device, indicated in a general way by 8, the arrangement being such that when the shell is pushed into 60 the slots and shoved downwards it becomes mechanically attached to the face plate and cannot be reversely moved except by manipulating the latch.

The shell carries a threaded boss 9, riveted 65 to it, which is adapted to support the fixture, and it is also provided preferably with a number of lateral openings such as 10 affording access to the interior.

The prongs 3 carried on the plug as above 70 stated, are adapted to be pushed through slots in the outlet structure into engagement with corresponding contact-terminals 26, inside the outlet receptacle and which are connected with the house-wiring circuit as 75 indicated. When the prongs are entered in their slots the shell is moved downwardly over and without moving the plug, to hook it, into the face plate. The structure above described is common in this art and forms 80 no part of this invention except as the latter is combined therewith and as will herein-after appear.

In standardizing such appliances, it has 85 been found necessary to make the shell so small and shallow that the use of molded insulating material in forming the attachment plug 2 makes the latter exceedingly fragile, inasmuch as a piece of molded composition sufficiently thin to fit and have 90 movement within the restricted space and containing the necessary wire passages is so weak as to break frequently under the strains of the screw driver when fastening the fixture wires to the binding screws. 95

In accordance with this invention, the plug 2 is formed of several laminæ of insulating material, preferably vulcanized fibre or equivalent sheet insulation. These laminæ are cut to the desired contour and appropriately punched, and then assembled and permanently fastened together by clenched staples 11 (Fig. 7), to form a compact, strong, unitary plug structure. One of the medial laminæ marked 12 directly supports the 100 metal prongs 3, secured thereto by eyelets 13, the interiors of which eyelets are threaded to receive the binding screws 4. 105

Above this prong-supporting member are assembled the two laminæ 14 and 15 which are identical in contour and may therefore be made in the same dies. These laminæ are centrally slotted to form a channel 16 in the assembled structure surrounding the bases of the prongs and adapted to accommodate the wires leading to the latter.

Beneath the member 12 are assembled the 10 pairs of laminæ 17 and 18. The former are duplicates of each other and have holes 19 to receive the heads of eyelets 13 in the assembled structure while the pair of laminæ 18, also of the same contour and duplicates 15 of each other, serve to cover the holes 19 and the eyelet-heads in the assembled structure.

The laminæ are all provided with registering holes 20 for the staples 11, or equivalent fastening means, and some or all are 20 notched peripherally, to form, in combination, the slots 21 and the corner recesses 22. The medial member 12 has a central hole 23 through which the fixture wires pass from the channel 16 adjacent the prongs to the 25 space or channel between the pairs of laminæ 17 and 18.

The plug 2 is assembled with the shell 1 as shown in Figs. 1, 2, and 3 and retained 30 therein by a lug 24 on one end of the shell and a screw 25 in the other end, which permit it to slide in, or relatively to, the shell

as the latter is hooked into or removed from the face plate.

The plug 2 does not share in the movement of the shell by which it is attached to 35 the face plates but can only move toward or from the plate, because its prongs 3 can move only in substantial parallelism with the fixed contact-terminals 26 contained by the receptacle, and accordingly the shell 1 40 has a bodily movement relatively to the plug 2, consequently the plug is shorter than the shell, as best seen in Fig. 3. The retaining lug 24 and the screw 25 enter the corner recesses 22, while the end slots 21 provide 45 clearance of the moving parts of the latch device 8, the plug being reversible, end for end, within the shell.

I claim:

In an electrical connector device, a plug 50 comprising in combination a plurality of laminar insulating members, staple means for binding said members together to form a unitary body, current carrying prongs, internally threaded eyelets extending through 55 one or more of the intermediate members and securing the prongs thereto and binding screws engaging the threaded portions of the eyelets.

In testimony whereof, I have signed this 60 specification.

MONROE GUETT.
